UNITED STATES PATENT OFFICE.

CHARLES P. B. EHRENTRAUT, OF PITTSBURG, PENNSYLVANIA.

FIRE-ESCAPE.

SPECIFICATION forming part of Letters Patent No. 470,112, dated March 1, 1892.

Application filed April 11, 1891. Serial No. 388,552. (No model.)

To all whom it may concern:

Be it known that I, CHARLES P. B. EHRENTRAUT, a citizen of the United States, residing at Pittsburg, in the county of Allegheny and State of Pennsylvania, have invented certain new and useful Improvements in Fire - Escapes; and I do hereby declare that the following is a full, clear, and exact description of the invention, which will enable others skilled in the art to which it appertains to make and use the same, reference being had to the accompanying drawings, which form a part of this specification.

My invention relates to improvements in portable extension fire-escapes of the class known as shooting ladders and trucks, and has for its object to provide a ladder which may be erected independently at a sufficient distance from a burning building to be out of the way of the smoke and fire and which can also be folded into a small space, both as to height and length, for transportation; furthermore, to provide means for bracing the ladder in its extended position to prevent it from swaying and also prevent it from bending or bulging at any point of its length; furthermore, to provide automatic means for bracing the ladder which will adjust themselves as the ladder is extended; furthermore, to provide a ladder which may be extended to any desired height and will be automatically locked at the desired extension, thereby relieving the hoisting-cables of strain while the ladder is in use; furthermore, to provide an effective elevator or basket which will operate upon and be supported by the ladder, and, furthermore, to provide means for spanning the interval between the top of the ladder and the building and to provide a platform upon which firemen may stand to throw water into the building.

With these objects in view the invention consists in the construction and arrangement of the sections of the ladder whereby their front surfaces are in approximately the same plane, in the construction of the truck whereby the base of the ladder may be leveled independently of the wheels, in the arrangement of guy-ropes to connect the top of the upper section to the windlass or drum on the truck, in the arrangement and adaptation of

the bracing-ropes and strut-frames to maintain the sections in a straight line and prevent bending or bulging, in the construction and arrangement of the means for operating said bracing-ropes and strut-frames whereby they are automatically adjusted as the ladder is extended, in the construction and adaptation of the locking device for maintaining the several sections at the desired extension (partial or complete) whereby the hoisting-cables are relieved of strain during the time that the ladder is in use, in the arrangement and adaptation of the guide-ropes for the elevator whereby it is supported throughout its descent and prevented from descending too precipitately in case of accident to the operating-cable, in the construction of the folding platform at the top of the upper section, and in the adaptation of the means for spanning the interval between the ladder and the building.

The invention consists, furthermore, in certain details of construction and arrangement, which will be fully described hereinafter in connection with the drawings, wherein—

Figure 1 is a view of the ladder in its extended or elevated position. Fig. 2 is a view of same in its folded position. Fig. 3 is a rear view of the ladder in its extended position. Fig. 4 is a vertical sectional view on line *xx* of Fig. 3. Fig. 5 is a detail view showing the retaining-lock. Fig. 6 is a detail sectional view on line *yy* of Fig. 3 to show the means for adjusting the strut-frames. Fig. 7 is a detail view of the yoke for connecting the front guy-ropes to the top section. Fig. 8 is a cross-section on line *zz* of Fig. 2. Fig. 9 is a view of the upper end of the ladder, showing the bridge in position. Fig. 10 is a view in detail of the folding platform. Fig. 11 is a view of one of the supporting-bars and the grappling-hook at the end of the same. Fig. 12 is a detail view showing groove and rib. Fig. 13 is a detail view showing hook and clasp for securing the platform-guards. Fig. 14 is a detail view of the alarm. Fig. 15 is an enlarged view of a portion of the machine, showing more particularly the arrangement of the several parts at the lower end of the same.

The truck A may be of any preferred form, is mounted upon wheels in any ordinary man-

ner, and is provided with a supplementary adjustable platform B, which is engaged by vertical adjusting-screws *a a*. The adjusting-screws are provided with miter-pinions *a' a'*, which are engaged by similar pinions *b' b'* on the operating-rod B'. Guard-flanges B'' B''' are secured to the truck on opposite sides of the adjustable platform and close to its edge to steady it and prevent straining and jamming the adjusting-screws.

The ladder is composed of a series of independent sections, of which the bottom or base section C is the broadest. The next section C' is narrower than the base section, so that its side beams will fit snugly between the side beams of the base-section. The next section C'' is narrower than section C' and fits between its side beams, and so on. The top section C''' is the narrowest and fits between the side beams of the next lower section C''. Thus the sections are telescoped, the contiguous sides of the side beams being provided with intermeshing or engaging ribs and grooves *c c*, respectively. The ribs of the ladder-sections are arranged close to the rear edges of the side beams, as are also the cross-bars and braces between the side beams, whereby the sections may be fitted together, so as to bring their front sides approximately in the same plane. The side beams may be reduced in thickness toward the upper end of the ladder, thus enabling the sections to be still more compactly folded. The side beams are also connected by cross-bars *v* and *v'* at their upper and lower ends, respectively, and intermediate brace-bars *v''*, said cross-bars *v* and *v'* being provided at their front sides with anti-friction rollers *v'''*, for a purpose to be hereinafter described.

The base-section is pivoted to adjustable standards D D, which are perforated to slide upon horizontal guide-rods *d d* at the sides of the adjustable platform, said guide-rods being secured at their ends to vertical posts *d' d'*. The adjustable standards D slide at their bases in channels D' D' in the surface of the adjustable platform. The base-section is arranged to lie flat upon the truck when the ladder is folded, in which position the sliding or adjustable standards D are moved to one end of the guide-rods, and when the latter is to be erected said standards are moved to the center of the truck and locked to the guide-rods by means of set-screws *d''*. Adjustable props D'' are fitted at their upper ends in caps or sockets *d'''* on the side beams of the base-section and rest at their lower ends upon the ground or pavement.

The side beams of the sections are provided at their upper and lower ends with small sheaves or pulleys *e e*, around which is passed the hoisting-cable E. Both ends of the cable are reeled upon the windlass E', which is mounted transversely on the truck, and the loop or central portion thereof passes under the two sheaves at the bottom of the

top section. From this point the sides of the double cable pass over the sheaves at the top of the second section, thence under the sheaves at the bottom of the second section, thence over the sheaves at the top of the third section, and so on until they reach the sheaves at the bottom of the base-section, from whence they pass to the windlass. By winding the ends of the cable upon the windlass the sections are successively extended, the top section being first elevated to the limit of its movement, and then the second section being similarly operated, and so on. Each section in turn, beginning with the top section, will be entirely extended before the next lower section is moved.

The object in forming the hoisting-cable in a single continuous piece and not securing it to either of the sections is to prevent twisting and straining in case one end of the cable is reeled more rapidly than the other. The cable is so arranged that it may adjust itself to make the draft upon the two sides equal. The sheaves at the upper end of the top section are omitted, as will be seen by reference to the drawings.

The side beams of the sections are further provided at their lower ends with small shoulders F F, which impinge against stop-blocks F' F' at the upper ends of the adjoining sections when the latter are extended to prevent disconnection of the sections, and said side beams are also provided at their lower ends with inwardly-projecting stop-pins F'' to hold the lower ends of the sections in alignment when the ladder is folded. These stop-pins project out into the path of the sections as they are folded, and the lower ends of the side beams come into contact with the pins and are thereby prevented from passing beyond the ends of the adjoining sections.

To maintain the sections at the desired height and relieve the hoisting-cable of strain after the desired adjustment is attained, I employ automatic locks f, which are set in the inner sides of the side beams and engage notches f' in the outer sides of the contiguous beams. The form of lock which I prefer to use in this connection is illustrated in Fig. 115 and is provided with a spring-actuated bolt f'', which is inclined upward toward its nose or engaging end or beveled, so as to prevent the sections from closing accidentally, but not interfere with the extension of the same. Said locks are also provided with a tumbler f''', which is adapted to be turned by means of a key and is arranged to engage a lateral lug on the bolt. The tumbler is so arranged that when turned fully around, as shown in dotted lines in the above-mentioned figure, it locks the bolt in its retracted position. It is necessary to lock all of said spring-actuated bolts in their retracted positions before the ladder can be folded. Any other suitable form of lock may be used; but I have found the one above described to be effective and

simple, and therefore prefer it to others which are more complicated and have no provision for locking the bolt in its retracted position. The ribs are preferably placed upon the inner sides and the grooves in the outer sides of the side beams, as shown in the drawings, in which case the lock forms a part of the rib, and the notches are formed in the grooves; but this arrangement may be reversed and 5 the ribs placed upon the outer and the grooves in the inner side. The notches may be placed at any suitable intervals. After the ladder is extended to the desired height, the hoisting-cables are slackened and relieved of strain, 10 the sections being supported by the automatic locks.

The front and rear guy-ropes G and G' are connected at their upper ends to the top of the upper section and are reeled at their 20 lower ends on a drum G'' near one end of the truck. The front guy-rope is connected at its upper end to a folding yoke G''', which is pivoted to the upper end of the top section, whereby said rope is held out of the way of 25 the elevator. The rear guy-rope passes from the drum around certain pulleys g g' on the truck and thence to the top of the ladder. These guy-ropes steady the ladder and prevent swaying when in use. The drum G'' is 30 provided with a pawl and ratchet, which prevent it from turning to slacken the ropes, and said pawl and ratchet must be disengaged when the sections are being elevated, after 35 which the drum should be rotated sufficiently to tighten the ropes.

In addition to the guy-ropes I employ bracing or supporting cables H H, which are arranged on the rear side of the ladder, are secured at their upper ends to the top of the 40 top section, and are reeled at their lower ends on a drum H', which is mounted on the side beams of the base-section. Each section, except the top section, is provided at its upper end with a pivoted strut-frame I, which consists of side arms K K, pivoted to the inner 45 sides of the side beams, and a cross-bar K', which connects the outer ends of said arms and is notched to receive and retain the bracing-ropes and hold them away from the ladder. The drum H' is provided with a pawl 50 and ratchet and with a crank whereby it may be turned. While the sections are being elevated the pawl and ratchet are disengaged to allow the drum to turn freely, and when the 55 sections are arranged at the desired height the pawl and ratchet are engaged and the drum is turned by means of its crank to tighten the cables, thereby forming a truss with a strut at each joint of the ladder to prevent bending or bulging. These strut-frames have their 60 side arms extended beyond their pivots to form detents k k, which bear against the side beams of the next upper section, and thereby hold the frames in their folded position flat against the section. When, however, said 65 next upper section reaches the limit of its

vertical extension, small notches k' near the lower ends of its side beams engage the said detents and extend the frames to a horizontal position. Stop-pins k''' are arranged in 70 the side beams to limit the swing of the frames and hold them in their horizontal position. Thus these strut-frames are adjusted successively and automatically as the sections are extended.

The elevator is another important feature of my improved fire-escape, and its basket L is supported and operated by means of a cable L', which passes over a roller L'' at the upper end of the top section and is reeled upon 80 a drum L''' at the foot of the ladder. M M are clutch-ropes secured at their upper ends to the upper end of the top section and reeled at their lower ends on a drum M', having a pawl and ratchet to prevent it from unreeling 85 prematurely. The elevator-basket is provided at its back with the pairs of parallel clutch-rolls N N, between which the clutch-ropes extend and by means of which said ropes are clutched to prevent the basket from 90 descending too precipitately in case of accident to the cable L'. Said ropes also act as guides to hold the basket in place on the ladder. The basket is still further steadied and guided by bearing upon the cross-bars of the 95 sections, the anti-friction rollers V''' being designed to enable the basket to ride freely over the lower cross-bars.

A folding platform O is pivoted to the side bars of the top section near its upper end, 100 and to the side of the platform are pivoted the guards P P, the bottom rails of said guards forming the pivots. The top rails of the guards are provided at their rear ends with hooks or detents p p, which engage notches p' 105 p' in the upper ends of the side beams of the section, and sliding clasps P' P', which are mounted upon the top rails, are adapted to be moved rearwardly to engage over the upper ends of the side beam to lock the rear ends 110 of the rails in place. When not in use, this platform may be folded up between the side bars of the section. The upper ends of the side bars of the ladder-section are reduced, so as to present shoulders 2, upon which the side 115 bars of the platform rest, and the platform is pivoted to the ladder-section just above the said shoulders by suitable pins, as shown in Fig. 10.

Q represents a horizontal supporting-bar, 120 two of which are extended between the platform D and the roof or a window-sill of the burning building. These bars are provided at one end with a grappling-hook Q', (see Fig. 11,) having a sliding jaw Q'' to engage 125 the outer side of the wall of the building, the operating-cord Q''' being connected to said jaw to enable it to be forced outwardly by a person standing upon the platform. The other end of one of the supporting-bars is inserted in a socket q at the outer end of the 130 platform and is locked therein by a clamp R,

the corresponding end of the other bar being fitted in a socket q' , which is provided with a set-screw R' . These supporting-bars are adapted to be covered by cross-bars $S S$, which 5 may be connected by means of flexible strips or webbing $s s$, whereby a mat is formed. This mat may be rolled into a small bundle for transportation and may be readily spread over the supporting-bars to form a flooring to 10 enable persons in the building to reach the ladder in safety.

From the above description it will be seen that when folded the ladder occupies but little space. The sections are fitted together closely, 15 so as to bring them into approximately the same plane, and the various bracing and strengthening devices which I employ enable the ladder to be made in short sections, which can therefore be carried by a short truck. It 20 is obvious that a short truck can be more easily handled in passing through the streets of a city and short sections can be more easily operated than longer ones and with less danger of accident.

25 At the top of the upper section is arranged an automatic alarm or stop T for the elevator, consisting of a vertically-movable bolt, which may be mounted in the yoke for the front guy-rope, to which is connected a line T' , 30 which extends to an alarm (of any suitable kind) or to the valve of the engine, which is used for operating the drum of the elevator-cable to warn the operators that the elevator has reached the top or (in case of an engine) 35 to check the rotation of the drum. Neither the alarm or engine is shown in the drawings, as these may be of any preferred or convenient form and such as are used in connection with other elevators. The adjustable truck-40 platform enables the ladder to be leveled when the wheels of the truck are upon uneven ground, as when the wheels on one side are in a gutter in the street. The drums are provided with pawls and ratchets to enable the 45 cables to be tightened, as described, to firmly brace the ladder and prevent swaying and bending while in use. The drums are also, preferably, provided with brakes (not shown) 50 to regulate the speed of the drums while the ladder is being folded.

Having thus described my invention, what I claim, and desire to secure by Letters Patent of the United States, is—

55 1. In a fire-escape, the combination of the telescoping sections, the guide-rods $d d$, the adjustable standards sliding upon said guide-rods and having the bottom or base section pivoted thereto, and set-screws to lock the standards to the guide-rods, substantially as 60 specified.

65 2. In a portable fire-escape, the combination, with a ladder, of the adjustable truck provided with parallel guide-rods $d d$, the adjustable standards sliding upon said guide-rods and having the ladder pivoted thereto, and set-screws to lock the standards to the 70 guide-rods, substantially as specified.

3. In a fire-escape, the combination of the telescoping sections provided with a hoisting-cable, the elevator operating between the side beams of said sections and provided with an operating-cable, the clutch-ropes secured to the sections, and the clutch-rollers mounted on the elevator and engaging the clutch-ropes, substantially as and for the purpose 75 specified.

4. In a fire-escape, the combination of the telescoping sections provided with a hoisting-cable, the elevator operating between the side beams of the sections, the clutch-ropes 80 secured at their upper ends to the upper end of the top section and reeled at their lower ends on a drum at the lower end of the base-section, and the clutch-rolls mounted on the rear side of the elevator to engage the clutch-ropes, substantially as and for the purpose 85 hereinbefore specified.

5. In a fire-escape, the combination of the telescoping sections, the elevator operating between the side beams of said sections and 90 provided with a hoisting-rope, and the alarm or signaling device consisting of a vertically-movable bolt arranged in the path of the elevator and provided with a line to extend to the base of the ladder, substantially as specified. 95

6. In a fire-escape, the combination of the telescoping sections, the adjustable bracing or supporting cables extending from the upper end of the top section to the base-section 100 and reeled upon a drum, the adjustable truss-frames pivoted to the sections near their upper ends and provided on their side arms with extensions or detents to be engaged by notches near the lower ends of the side beams 105 of the sections, all constructed and arranged substantially as and for the purpose specified.

7. In a fire-escape, the combination of the telescoping sections mounted upon a truck, and the front and rear guy-ropes connected 110 at their upper ends to the top section and reeled at their lower ends on a drum on the truck, the front guy-rope being secured to the outer end of a folding yoke G'' on the top section, all substantially as and for the 115 purpose specified.

8. In a fire-escape, the combination, with the sliding sections, of a folding platform pivoted to the top section and provided at its sides with pivoted guards $P P$, the said guards 120 being adapted to engage the top section, substantially as specified.

9. In a fire-escape, the combination, with the sliding sections, of a folding platform O , pivoted to the top section, the folding-guards $P P$, pivoted at their bottoms to the said platform and provided at their upper sides with hooks or detents $p p$ to engage notches in the top section, and the sliding clasps $P' P'$, mounted upon the guards to engage the side beams of the top section to lock said hooks or detents in place, substantially 125 as and for the purpose specified. 130

10. In a fire-escape, the combination, with

telescoping sections, of a folding platform O, pivoted to the top section, the supporting-bars provided at their outer ends with grappling-hooks Q' and sliding jaws Q'' and engaged at their inner ends in sockets q and q' in the platform, and the mat composed of transverse slats connected by webbing arranged upon said supporting-bars, all con-

structed and arranged substantially as specified.

In testimony whereof I affix my signature in the presence of two witnesses.

CHARLES P. B. EHRENTRAUT.
